HARVEY DESCHERE, OF NEW YORK, N. Y.

ELECTRIC SIGN.

1,091,916.

Specification of Letters Patent. Patented Mar. 31, 1914.

Application filed July 3, 1913. Serial No. 777,146.

To all whom it may concern:

Be it known that I, HARVEY DESCHERE, a citizen of the United States, and a resident of the borough of Manhattan, in the city, county, and State of New York, have invented certain new and useful Improvements in Electric Signs, of which the following is a specification.

This invention provides an improved form of electric sign for use particularly in window display, the object being to produce a sign of attractive appearance and one in which the illumination of the characters, even when viewed at a very acute angle to their faces, is of such nature as to render them perfectly distinct.

The object is, further, to provide a sign element or character of durable and compact construction which includes provisions whereby the destruction of one of its lamps will not cause the whole letter to be darkened, and which is adapted for convenient assemblage with other characters to form a sign which obstructs as little as possible the view of objects behind it.

In the accompanying drawings illustrating the invention: Figure 1 is a perspective view of a sign embodying the invention; Fig. 2 is a rear view of one of the characters, the base being sectioned and the filling for the back channel omitted; Fig. 3 is a bottom plan of the base of Fig. 2; Fig. 4 is a vertical transverse section taken through the right side of Fig. 2; Fig. 5 is a typical cross-section; and Fig. 6 is a diagrammatic view of the wiring arrangement.

The invention includes a novel kind of illuminated character, which may be a letter, figure, symbol or the like, and which is assembled with other characters of like construction to produce a sign of any desired lettering. These sign elements are designated 10 in the several views, and it will be understood that their construction is substantially alike though their forms naturally differ.

Each element comprises a channeled body 11, mounted on an individual base 12, which enables it to be assembled side by side with other elements on a suitable common support, such as 13, to form the sign. The body 11 corresponds both in outline and in its channeling 14 to the letter or other character which it represents; and the marginal walls 15 are preferably comparatively narrow with respect to the face of the sign, so

that the body constitutes in effect an outline character, within which are located separate, dwarf incandescent electric lamps 16. The latter are held in suitable sockets 17 mounted in and substantially flush with the back wall 18 of the front channel; and the depth of the channeling is such that the lamps are largely or entirely included within the front lines of the body, so that the lateral light rays are cut off, and hence the spaces between the letters and the spaces within the letters, such as the openings through the loops of the letter "B" for example, are entirely without illumination, and their blackness contrasting with the sharply illuminated characters renders the sign especially readable. The effectiveness of the sign is increased by coating the surfaces of the channels of the characters with a white or other reflecting enamel 19, which is preferably also applied to the external surfaces of the body, though the outside finish may be varied as desired. In a sign thus constituted the illumination of each character is so brilliant and sharply defined that even when the sign is viewed at an acute angle, or almost parallel to its face, the several characters are distinct and do not blur.

As shown, the character is hollow at the back, as well as at the front; and the back channel 20 is utilized for housing and protecting the rearwardly-projecting sockets 17 and the connections 21 leading thereto. The body of the character thus consists in effect of marginal flanges 15, 22 and a septum wall 18, which form the front and back channels and present a characteristic H-shaped section, as shown in Fig. 5.

When the character is completed the rearwardly-projecting sockets and the wires are still further protected by an insulating cement or mass 23, which is filled into the back channel, preferably flush with the rear edges 22 of the flanges 22, so as to present a plane back, which may be coated with paint or enamel or otherwise finished. The wires 21 pass into the back channel from the base through openings 24 in the flange portion 22 at the bottom of the body, and at their outer ends are connected to the upper ends of posts 29, which pass through the base behind the character. The upper ends of these posts and the portions of the wires connected thereto are preferably disposed in a groove, which may be closed in a suitable

manner. The wiring is such that the several lamps of each letter are connected in series. In order that the destruction of one lamp may not extinguish the whole series, 5 I mount supplementary resistances 27 on the base, one of these resistances being connected in shunt with each lamp, as indicated in the diagrammatic view, Fig. 6, so that, if a lamp breaks, the current to supply the 10 remainder can still pass by way of its shunt. An advantageous construction is obtained by disposing these resistances transversely of the bottom of the base, where they are held in suitable grooves 28 with their ends 15 secured to the lower ends of the posts 29. The supplementary resistances are proportioned so that a suitable amount of current flows through them normally, and in event of any of the lamps breaking, the corresponding resistance or resistances carry the 20 entire current for the remaining lamps, which therefore continue to burn. The connections for supplying the character with current are indicated at 30, 31 in Fig. 2, 25 and it will be obvious that the several letters of the sign may be connected in series, or in parallel circuits as preferred.

It will be observed that the sign as assembled is of an open character, which is an

advantage because in daylight it does not 30 constitute an obstruction in a show window.

While I have described the preferred embodiment of my invention with considerable particularity, it will be understood that the construction and arrangement of wiring are 35 susceptible of variation without departing from the scope of the invention as defined by the claim.

What I claim as new is:

An electric sign element comprising a 40 body mounted on a base, said body in the form of a character and having marginal flanges and a septum wall constituting channels both at the front and back, lamp sockets mounted in the septum wall and projecting rearward into the back channel, connections passing from the base through openings in the bottom flanges into the back channel, and insulating material filling the back channel and in which said sockets and 45 connections are embedded.

In witness whereof, I have hereunto set my hand this 30th day of June, 1913.

HARVEY DESCHERE.
